UNITED STATES PATENT OFFICE.

JESSE C. SIMMS, OF MATOAKA, WEST VIRGINIA.

ARTIFICIAL MINNOW.

1,079,891.

Specification of Letters Patent. Patented Nov. 25, 1913.

Application filed March 28, 1913. Serial No. 757,413.

To all whom it may concern:

Be it known that I, JESSE C. SIMMS, a citizen of the United States, residing at Matoaka, in the county of Mercer and State 5 of West Virginia, have invented new and useful Improvements in Artificial Minnows, of which the following is a specification.

This invention relates to artificial minnows, designed either for still fishing or 10 trolling, the object of the invention being to provide a minnow having an electric lamp concealed therein and providing a luminous lure, whereby the fish will be attracted.

A further object of the invention is to 15 provide a minnow having a body constructed of glass or similar material to transmit the light rays from the lure, whereby the efficiency of the device will be increased.

The invention consists of the features of 20 construction, combination and arrangement of parts hereinafter fully described and claimed, reference being had to the accompanying drawings, in which:

Figure 1 is a side elevation of one form of 25 artificial minnow embodying my invention. Fig. 2 is a horizontal longitudinal section of the same. Fig. 3 is a similar view showing a modified construction. Fig. 4 is a dia-grammatic view of the light circuit.

Referring to Figs. 1 and 2, 1 designates 30 the body and 2 the head of the minnow, which are threaded or otherwise detachably connected, as at 3. The body 1 is made of glass, while the head 2 may be made of glass 35 or other suitable material, preferably of a nonconducting character.

The head 2 has a portion 4 forming the 40 bulb of an electric lamp 5, and is hollowed or chambered to receive a longitudinally extending body 6 of fiber or other nonconducting material, from which extend the lamp terminals 7 and 8. The body 1 is provided at its forward end with a cavity 11, to partially inclose the bulb 4, the sides of which 45 cavity converge rearwardly and communicate with a longitudinal passage 12 terminating in a tail portion 13 fixed to the rear end of the body. Suitably secured to the head 2 are arms or other carrier members 14

50 provided with gang hooks 15 and suitably secured to the tail piece 13 are gang hooks 16. Upon the head and tail piece may be provided suitable planes or guiding projections 17, simulating fins.

55 In practice, I may employ a dry battery housed within the head 2, and suitably con-

nected with the lamp terminals, and associated with a suitable switch for cutting out connection between the battery and terminals. In the present disclosure, however, I 60 employ a line 18, comprising a covering of nonconducting material through which conductor wires 19 and 20 extend, as in an ordinary lamp cord construction. These wires are suitably fastened to the end of the head 65 2, and from this point the covering is branched, as at 21, and extended through opposite sides of the lamp chamber and into the cavity 11, and thence continue in a single section through the passage 12, where the 70 end of the cord is terminally connected with the tail piece 13 in any suitable form and insulated manner. The line is thus firmly fastened to the minnow body, in such a manner as to withstand all shocks, jars and strains. 75 A suitable switch 22 may be provided for connecting the terminals or conducting wires at a point in proximity to the binding posts, to make or break the current connection between the source of electric energy and the 80 lamp, or an equivalent switch device may be provided at the proximal end of the line.

In the modified construction of my invention shown in Figs. 3 and 4, the cavity 11 and passage 12 are dispensed with, and the 85 branches 21^a of the line extend on the outside of the minnow and are terminally fastened to the tail piece. This construction may be employed in the cheaper types of minnows, but is not considered so desirable 90 as that disclosed in Figs. 1 and 2. If desired, a swivel may be provided at some suitable point in the line connection to permit the minnow to have rotary motion.

It will be seen from the foregoing description that my invention provides a minnow composed of detachably connected head and body sections, within the head section of which an electric lamp is inclosed, the rays from which will be projected outwardly, thus 100 providing a luminous lure. It will also be seen that these rays shine through and are refracted by the glass body, thus increasing the efficiency of the lure.

While the current supplying connection 105 may be arranged as described, it will of course be understood that modifications in this respect may be made within the spirit and scope of the invention.

I claim:

1. An artificial minnow comprising connected body and head sections, said body sec-

tion being constructed of glass, and an electric lamp housed within the head section so as to transmit the rays outwardly therefrom through the glass body.

5. An artificial minnow comprising connected body and head sections, said body being formed of glass and having a cavity therein, an electric lamp secured to the head section and including a bulb projecting into 10 the body section to transmit the light rays therethrough, and a line including suitable current supplying connections.

3. An artificial minnow comprising connected body and head sections, said body section being formed of glass and having a 15 cavity therein and a passage leading there-

from, an electric lamp inclosed within the head section and having its bulb projecting partially into said cavity, and a line provided with conductors connected with the 20 lamp terminals, said line having a portion branched and extending through the head and cavity and its terminal end extending through said passage and fixed at the tail of the body. 25

In testimony whereof I affix my signature in presence of two witnesses.

JESSE C. SIMMS.
